UNITED STATES PATENT OFFICE

119,523

DESIGN FOR A DESK LAMP

Clyde D. McCann, Des Moines, Iowa

Application June 28, 1939, Serial No. 85,733

Term of patent 14 years

To all whom it may concern:

Be it known that I, Clyde D. McCann, a citizen of the United States and resident of Des Moines, Polk County, Iowa, have invented a new, original, and ornamental Design for a Desk Lamp, of which the following is a specification, reference being had to the accompanying drawing, forming a part thereof.

Fig. 1 is a front elevational view of a desk lamp showing my new design; and

Fig. 2 is a side elevational view thereof:

I claim:

The ornamental design for a desk lamp, substantially as shown.

CLYDE D. McCANN.
